IMPROVEMENT IN HYDRO-CARBON HEATING APPARATUS.

OSCAR F. MORRILL, OF CHELSEA, MASSACHUSETTS.

Letter's Patent No. 60,224, dated December 4, 1866.

SPECIFICATION.

TO ALL WHOM IT MAY CONCERN:

Be it known that I, Oscar F. MORRILL, of Chelsea, in the county of Suffolk, and State of Massachusetts, have invented improvements in Heat-Generating Hydro-Carbon Burning Apparatus; and I do hereby declare that the following, taken in connection with the drawings which accompany and form part of this specification, is a description of my invention sufficient to enable those skilled in the art to practise it.

This invention relates to peculiarities of construction in that class of apparatus designed for burning fluid hydro-carbons with a tubular wick, the object of said peculiarities being, first, to lessen conduction of heat to the wick to such an extent that the wick will not become charred; and second, to regulate the height of the flame when irregular and caused by a wick of uneven height.

Figure 1 of the drawings is a sectional elevation of that part of a hydro-carbon burning apparatus embodying my present invention, the section being taken in the plane of the line $z z$, seen in

Figure 2, which is a horizontal cross-section taken in the plane of the line $y y$, seen in fig. 1.

The wick is contained in or between the tubes a and b , the lower ends of which enter into the liquid hydro-carbon in a reservoir not shown in the drawings. Surrounding the upper end of tube a is a shell of metal, d , of a flattened spheroidal shape, which is connected with tube a , by a filling of plaster or other similar non-conductor, c . The outer foraminous chimney rests on the metal d , in a suitable annular groove formed therein, as shown. It will be seen from inspection of fig. 1, that the metal d does not connect with or touch the metal of the wick tube a , d being supported on the plaster filling, c , adhering to the tube a , there being left between the metallic parts a and d the spaces seen in fig. 1, marked 1 and 2. The piece d has by its shape a large extent of radiating surface, which, as it is fully open to the air, dissipates by radiation a large portion of the heat received from the outer foraminous chimney, e , while the heat not radiated therefrom is conducted so slowly by the plaster c , and is distributed thereby over so large a surface of the wick tube a , that its temperature is thereby lessened to a degree which will not injure or char the wick. Within the inner wick-tube b is located a smaller tube, f , which is expanded and shaped at its top, as clearly seen in fig. 1, so as to receive and support the inner foraminous chimney, g . Between the tubes b and f is a plaster or other similar filling, h , disposed as shown, so that there is no metallic communication between b and f , there being spaces, 3 and 4, between said tubes, occupied by the filling alone, so that the heat conducted from g to f , that is not radiated from the inner surface of f , is distributed by the filling over so great an extent of the inner wick-tube as to reduce its temperature to a degree that will not injure the wick. The upper part of g is provided with a cap, i , in the centre of which is made a nut which fits the screw-threads on rod j . This rod j extends down into the inner wick-tube b , and is provided at its lower end with springs, k , which, pressing outward on tube b , support and hold the rod j , and the inner chimney, g , in any position where, within reasonable limits, they may be placed. The object of this is to be able, by tipping slightly the tube g to any side, to diminish the space between e and g on one side and increase it on the other, for wherever the wick projects more on one side than it does on the other there it gives the longest flame, and by tipping the tube g toward the longest flame the flame is there lessened in area and the length of the flame is equalized, the tube g and the rod j being kept in position where placed by the action of the springs k , while by the screw on the upper end of j the parts may be adjusted as required, and provision is made for the necessary dismemberment of the parts.

I claim giving to the metallic casing d , surrounding and protecting the filling c , the spheroidal form shown, for the purpose of obtaining large radiating surface from which to dissipate the heat received from the chimney e .

Also, connecting the metallic covering d , by the filling c , with the outer wick-tube, when the spaces 1 and 2 intervene so as to cut off metallic connection, substantially as and for the purpose specified.

Also, connecting the tube f with the inner wick-tube b , by filling h , in such a manner as to cut off metallic connection by the spaces 3 and 4, substantially as described and for the purpose set forth.

And regulating irregularities of the length of the flame from the wick, by contracting the flue-opening on one side and increasing it on the other, substantially as and for the purpose specified.

OSCAR F. MORRILL.
